CLAIM

The ornamental design for a seat, as shown and described.

DESCRIPTION

FIG. 1 is a front elevational view of a seat showing my new design, the rear side view is a mirror image;

FIG. 2 is a right side elevational view of the seat shown in FIG. 1, the left side view is a mirror image; and,

FIG. 3 is a top plan view of the seat shown in FIG. 1.

The seat's legs are represented in dotted lines because they are purely functional and are not part of my design.
